DESIGN FOR A POWER PULVERIZER FOR
COMPOST AND THE LIKELeonard G. Hough and Robert J. Collins,
Toronto, Ontario, Canada

Application August 15, 1946, Serial No. 132,547

Term of patent 14 years

(Cl. D55—1)

To all whom it may concern:

Be it known that we, Leonard G. Hough and Robert J. Collins, citizens of Canada, both residing at Toronto, in the county of York and Province of Ontario, Canada, have invented a new, original, and ornamental Design for Power Pulverizers for Compost and the like, of which the following is a specification, reference being had to the accompanying drawing, forming part thereof.

Figure 1 is a perspective view of a power pulverizer for compost and the like, embodying our new design, and showing particularly the rear end and the top and one side thereof;

Figure 2 is a perspective view showing the other side and the front end thereof.

We claim:

The ornamental design for a power pulverizer for compost and the like, as shown.

LEONARD G. HOUGH.
ROBERT J. COLLINS.
